SPINDLE STRUCTURE

Rudolph A. Kowalsky, Woonsocket, R. I.

Application October 25, 1933, Serial No. 695,131

4 Claims. (Cl. 308—169)

The present invention relates to a spindle structure of the type adapted for use in connection with textile machines, and more particularly to a spindle structure of the character provided with a casing containing a spindle and having an oil inlet passage formed to communicate with the interior of the casing to make available a constant supply of lubricant for the spindle.

Heretofore great difficulty has been experienced in the use of spindle structures of this character in that the rapid rotation of the spindle within the bolster sets up strong currents in the oil which tend to draw the oil upwardly around the spindle more rapidly than it can be returned into the space within the casing where the bolster is located. No adequate means has been devised heretofore for preventing excessive upward movement of the oil throughout the length of that portion of the spindle located within the casing and no means has been found for returning this oil to the casing with sufficient rapidity to prevent oil from being carried over the upper end of the casing and sprayed over the machine frame, floor and textile material. This results not only in a considerable waste of oil but also in damaging the textile material and in soaking the floor and adjacent machine parts with oil, as well as in causing the spindle to run dry unless the oil is renewed frequently.

One object of the present invention is to overcome the discharge of oil from the casing through the rotation of the spindle at all times and under substantially all conditions of use.

Another object of the invention is to provide means for permitting a restricted supply of oil only to the spindle bearing whereby the amount forced upwardly by the rotation of the spindle is limited to such an extent as to prevent the discharge of excessive quantities of oil over the top of the casing.

A further object of the invention is the provision in a device of this character of one or more vertical grooves in the exterior surface of the upper enlarged portion of the bolster arranged to communicate with the reservoir portion of the casing and thus permit passage of the oil drawn upwardly by rotation of the spindle within the bolster back into the enlarged reservoir area.

Other objects and advantages of the invention relate to various improved details of construction and novel arrangements of the parts as will be more fully set forth in the detailed description to follow.

Referring to the drawings:—

Fig. 1 is a vertical sectional view through the spindle casing and oil supply spout showing the bolster and a portion of the spindle in side elevation.

Fig. 2 is a vertical sectional view, taken at right angles to the sectional view shown in Fig. 1, and showing the casing, bolster member and whirl in section and the spindle in elevation.

Fig. 3 is a vertical sectional view, similar to Fig. 1, and showing the casing, oil spout bolster member and whirl all in section with the spindle in elevation.

Fig. 4 is a transverse enlarged sectional view taken substantially along the line 4—4 of Fig. 1.

Fig. 5 is a transverse enlarged sectional view taken substantially along the line 5—5 of Fig. 1.

Fig. 6 is a transverse enlarged sectional view taken substantially along the line 6—6 of Fig. 1.

Fig. 7 is a transverse enlarged sectional view taken substantially along the line 7—7 of Fig. 1.

Fig. 8 is a transverse enlarged sectional view taken substantially along the line 8—8 of Fig. 1.

Fig. 9 is a transverse enlarged sectional view taken substantially along the line 9—9 of Fig. 1.

Fig. 10 is a transverse enlarged sectional view taken substantially along the line 10—10 of Fig. 1.

Fig. 11 is a detailed perspective view of the lower end portion of the bolster, and

Fig. 12 is a perspective view of the spring clip employed for maintaining the adjustable bearing in fixed relation with the lower end of the bolster member.

In that form of the invention shown in Figs. 1 and 2 of the drawings, 1 designates a spindle casing provided with a head-flange 2 and a depending tubular body portion 3 which is adapted to be inserted in an opening in a spindle rail and clamped thereto by a nut 4, which is threaded on the depending tubular body portion after a manner well-known in the art. The spindle casing 1 is provided with a central bore 5 which is adapted to receive a bolster 6 having a central bore 7 for receiving the lower end portion 8 of a spindle 9. The spindle 9 is provided with a whirl 10 as is usual in devices of this character. An oil supply spout 12 may be formed integral with the casing 1 and is provided with a hinged cover 14 which may be in the form of a pivoted detent for locking the spindle against accidental removal from the casing. The oil supply spout 12, as shown, is provided with a vertical oil passage 15 and a horizontal passage 16 connecting with each other, and the passage 16 communicates with the bore 5 of the casing for transmitting lubricant thereto. The bore 5 of the casing may be of substantially

20

30

35

40

45

50

55

uniform cross-section throughout the major portion of its extent but, as shown, is enlarged as indicated at 17, from a point indicated approximately by the reference character 18 to a point 5 adjacent to or slightly below the point of entry of the horizontal oil passage 16 into the casing, as indicated at 19.

The bolster 6 is provided with a central bore 7, as stated, to furnish a bearing for the lower end 10 portion 8 of the spindle, and the bore 7 may be inwardly tapered below the point 20 to substantially fit an external taper on the lower end portion 2 of the spindle 9.

The bolster 6 is provided, adjacent to the upper 15 end thereof with an enlarged external portion 22 which fits closely within the bore 5 of the casing and has one or more longitudinal grooves 23 formed upon the external face thereof to permit the flow of oil downwardly past the enlarged portion 22. A spline and groove connection 24 may also be employed between the external face of the enlarged portion 22 of the bolster and the inner face of the casing wall located adjacent thereto to lock the bolster against rotation relative to the casing.

Immediately below the enlarged portion 22 of the bolster, and beginning at substantially the point indicated by the reference character 18 on Fig. 1 of the drawings, the external diameter of 30 the bolster member is reduced, as indicated at 26, extending downwardly to a point substantially coincident with the lower portion of the enlarged recess 17 formed in the bore of the casing. The reduced external diameter of the bolster 26 and 35 the enlarged recess 17 formed in the bore of the casing are thus substantially co-extensive longitudinally of the bolster and serve to form an oil reservoir 27 extending substantially from the enlarged portion 22 of the bolster to a point which 40 may be slightly below or substantially coincident with the lower edge of the inlet passage 16, whereby unrestricted circulation of the oil may exist between the oil reservoir 27 and the vertical portion 15 of the oil inlet passage. The horizontal or transverse cross-sectional area of the oil reservoir 27 is preferably substantially equal to or greater than the horizontal or transverse cross-sectional area of the vertical oil supply passage 15 whereby the total volume of the oil in 45 the oil reservoir, when maintained, for instance, at the level indicated by 30, will be equal to or in excess of the volume of the oil in the passage 15, when maintained at the corresponding level indicated by 31.

50 Although I have shown and described the oil reservoir as being formed in the present case by reducing the outer surface of the bolster and forming a corresponding cooperating recess in the inner wall of the casing, because of the limits of tolerance imposed in the usual bolster and casing construction, it is to be understood that the invention contemplates the formation of the oil reservoir 27 either entirely within the outer surface of the bolster or entirely within the inner 55 wall of the casing in constructions where the size and proportion of the parts permit.

The bolster 6 is provided with a second enlarged portion 33 which may be located immediately below the space forming the oil reservoir 27, and 60 preferably flush with or slightly below the lower edge of the horizontal oil passage 16. This enlarged portion is adapted to fit closely within the bore 7 of the casing and may be provided with one or more vertical grooves 34 to permit oil to 65 pass downwardly from the reservoir 27 past the

enlarged portion 33. Immediately below the enlarged portion 33 of the bolster, the opposite side walls of the bolster may be cut away, as indicated at 35, to provide oppositely positioned longitudinal openings 36 in the bolster wall communicating with the bore 5 of the casing outwardly of the bolster and the lower end portion 8 of the spindle. The formation of these openings on opposite sides of the spindle reduce the bolster at that point to a pair of oppositely positioned longitudinal 10 bearings 37, which are each concavo-convex in transverse cross-section.

Immediately below the oppositely positioned openings 36, the bolster 6 may be provided with an enlarged portion 39 which is adapted to fit 15 closely within the bore 5 of the spindle casing. Below the enlarged portion 39 those side walls of the bolster angularly positioned with reference to those previously mentioned are cut away as indicated at 40, to provide oppositely positioned openings 41 in the bolster wall communicating with the bore 5 of the casing outwardly of the bolster and a portion of the spindle 8. The openings 41 formed in the bolster wall may be located at substantially right angles to the openings 36 previously described, and with the openings 36 they serve to provide a plurality of radial openings extending through the bolster wall and over a substantial portion of the circumference of the spindle in such a manner as to tend to break up 20 swirl currents generated by the rapid rotation of the spindle in the bolster. The cutting away of the bolster, as indicated at 40, provides a pair of oppositely positioned longitudinal bearings 42 in the bolster which are each substantially concavo-convex in transverse cross-section and which may be located at substantially right angles to the opposed bearings 37 previously described.

The circumferential enlarged portions or shoulders 22, 33 and 39 in conjunction with the intermediate reduced portions serve to provide oil chambers more or less isolated from each other for retaining considerable quantities of oil in a substantial rest.

That portion of the bolster 6 immediately below the vertical bearing portions 42 may be of a somewhat reduced external diameter, as indicated at 45, and terminates in an enlarged portion 46 which may fit closely within the bore 5 in the casing. The enlarged portion 46 of the bolster is provided upon its outer face with a circular groove 47 and a straight longitudinal groove 48 which intersect to form angularly extending surface grooves for the reception of a resilient locking member 50 having curved arms 51 adapted to fit within the circular groove 47 and a substantially straight arm 52 adapted to fit within the groove 48. The straight arm 52 is extended to form an end portion 53 projecting downwardly below the lower end 54 of the bolster proper. The enlarged portion 46 of the bolster is internally threaded, as indicated at 55, and an adjustable bearing member 56 is provided with a reduced externally threaded portion 57 adapted to be threaded within the internally threaded portion 55 of the bolster. The adjustable bearing member 56 has a further reduced portion 58 extending beyond the threaded portion 57 and adapted to project upwardly within the bore 7 of the bolster to serve as an adjustable support for the lower end of the spindle 8. The adjustable bearing member 56 is also provided with an enlarged portion 59 having a plurality of longitudinal grooves 60 formed therein, each adapted to receive the lower end portion 53 of the re- 70 75

silient locking member 50 for maintaining the adjustable bearing member in any one of a plurality of adjusted positions relative to the bolster 6 to support the tapered end portion 8 of the spindle in proper relation with the inner wall of the bolster member.

In that form of the invention shown in Fig. 3 of the drawings, the casing and bolster member are similar in all respects to those previously shown and described, except that the spindle line is of a slightly different type, requiring a casing of less length than those previously shown, and the spindle line is of a substantially uniform diameter throughout its central longitudinal portion to the point indicated by 60' from which point it has a tapered downwardly extending portion 61, of slightly greater taper than in the case of the forms previously shown. In each case the bore 7 of the bolster is shaped to correspond substantially with the taper of the lower end portion of the spindle.

In each form of the invention shown herein, the bolster member 6 may be provided with correspondingly positioned enlarged portions 22, 33, 39 and 46 located substantially after the manner indicated, and each of a diameter to fit substantially within the bore 5 of the casing 1. These enlarged portions serve to hold the bolster against vibration or radial movement within the casing and also serve to strengthen the bolster at suitable intervals to provide against breakage. A key and slot connection 24, as shown, or other suitable means, may be provided in each case for holding the bolster 6 against rotation relative to the casing.

The invention in each case is illustrated in connection with and is particularly adapted for use with a spindle casing of the type provided with an oil spout 12, or an equivalent, which is usually formed integral with the casing, and which is also provided with connecting oil passages, comprising a vertical oil passage 15 and a horizontal oil passage 16, identified as such in the normal position of the casing and with the horizontal oil passage in open communication with the vertical oil passage and the interior of the casing 1.

The objectionable discharge of oil from spindle bearings is generally attributed largely to currents set up by the rapid rotation of the spindle, which, through its rotation, causes swirl currents in the oil and has a tendency to draw or force the oil upwardly between the spindle and bolster to such a degree that it rises to a high level in the casing and accumulates upon the top of the bolster. This accumulation of oil at a high level in the casing tends to prevent a free downward flow of the oil which has been drawn up around the spindle above the bolster.

The oil, thus being prevented from returning to a lower level, accumulates above the bolster, and continued rotation of the spindle causes it to be thrown outwardly and sprayed over the floor, fabric and adjacent parts of the machinery.

To prevent this accumulation of oil at the top of the bolster, the swirl currents within the casing may be broken up or eliminated, or some means devised for preventing the oil level in the casing from rising sufficiently above the oil level in the vertical portion of the inlet passage to cause oil to be sprayed outwardly upon rotation of the spindle.

In order to reduce, to some degree, the upward flow of oil in the casing through the action of swirl currents caused by rapid rotation of the

spindle, the bolster may be cut away upon opposite sides, preferably at spaced intervals, as indicated at 35 and 40, to form opposed openings 36 and 41, the openings 36 being located in staggered relation with respect to the corresponding openings 41 circumferentially of the spindle. The provision of these openings in the bolster wall, which may extend throughout a considerable portion of the entire circumference of the spindle, tends to break up the swirl currents at a point 10 below the enlarged portion 33 of the bolster.

By providing enlarged portions such as 22 and 33 having small grooves 23 and 34 respectively formed in the outer faces thereof the free flow of oil from the inlet passage and reservoir to the 15 spindle bearing may be restricted to such an extent as to prevent the drawing of oil upwardly about the spindle in quantities sufficient to cause a considerable discharge of oil over the top of the casing.

The provision of the adjustable bearing member 56 serves to compensate for any wear upon the spindle end or bolster bearing and allows a ready adjustment of the spindle to secure the desired clearance between the tapered end of the 25 spindle and the bore 7 for the proper operation of the spindle.

The longitudinal grooves 23 formed in the outer surface of the enlarged portion 22 of the bolster member serves to permit any oil which may flow 30 over the top of the bolster member to pass downwardly into the reservoir 27, the oil level in the reservoir being kept sufficiently low by the means previously described to accommodate this overflow oil. Similarly the longitudinal grooves 35 34 formed in the enlarged portion 33 of the bolster permit a limited flow of oil past the enlarged portion 33, for the purpose of securing adequate lubrication, without allowing unrestricted transmission of the swirl currents or 40 their effect upon the oil content past that point.

What I claim is:—

1. In an independently lubricated vertical spindle bearing, a casing having a bore and provided with an oil spout having a vertical inlet 45 passage located in opposed relation to and communicating with the bore, a bolster member positioned within the casing having a central opening forming a spindle bearing and provided with enlarged circular shoulders fitting closely within 50 the casing and spaced from each other longitudinally of the bolster and a reduced portion located between said shoulders to provide an oil reservoir within the casing at the point of communication of the inlet passage with the bore 55 out of direct communication with the central opening of the bolster member, said circular shoulders being formed to prevent free flow of oil to and from said reservoir vertically of the bolster member, while said shoulders are shaped 60 to provide for a restricted flow of oil to and from said reservoir and the space within the casing bore outwardly of the bolster member and below said reservoir, said bolster member being provided below said circular shoulders and said 65 oil reservoir with openings for permitting a restricted flow of oil between the central opening of said bolster member and the part of the casing outwardly of said bolster member and below said oil reservoir, the parts being so proportioned as to restrict the flow of oil downwardly from said reservoir to such an extent that the amount of oil carried upwardly about the spindle within the bore of the bolster is limited to such a degree as to prevent accumulation of oil with- 75

in the casing above the uppermost circular shoulder in quantity sufficient to overflow the casing.

2. In an independently lubricated vertical spindle bearing, a casing having a bore, a bolster member positioned within the casing provided with a bore serving as a bearing for a spindle and having enlarged casing engaging portions spaced from each other longitudinally of the bolster member to provide an oil reservoir within the casing of substantial cross-sectional area outwardly of the bolster member and out of direct communication with the bore of the bolster member, a vertical oil inlet member having a passage 10 communicating with said oil reservoir adjacent to the lowermost part thereof, said lowermost enlarged casing engaging portion being shaped to restrict the free flow of oil from said reservoir downwardly of said bolster member while provided with means permitting a gradual and limited flow of oil from said reservoir whereby the flow of oil from said reservoir for application to the spindle bearing is reduced to an amount not substantially in excess of that required for proper lubrication to prevent discharge of oil over the top of the casing, said bolster member being provided below the lowermost of said enlarged casing engaging portions with restricted openings spaced from each other 25 to permit restricted areas of communication at circumferentially spaced points between the spindle bearing and the outer surface of the bolster member.

3. In an independently lubricated spindle structure, a vertical spindle casing provided with a longitudinal bore and having an oil spout provided with a vertical inlet passage a portion of which is laterally positioned with respect to and in open communication with a portion of the longitudinal bore of the spindle casing, a bolster member provided with a central longitudinal bore forming a spindle bearing and having spaced enlarged circular portions fitting closely within the bore of said casing and a reduced circular portion located between said enlarged circular portions and oppositely positioned relative to

the point of communication of said inlet passage when the bolster member is operatively positioned within the bore of said casing, each of said spaced enlarged circular portions being provided with a narrow opening to permit a gradual and restricted flow of oil past said circular portions, said bolster member being provided with vertically spaced sets of circumferentially spaced openings below the lowermost of said circular portions, forming points of communication between the spindle bearing opening and the outer surface of said bolster member, the openings of one set being staggered with respect to those of the other set.

4. A spindle bearing for preventing discharge of oil therefrom through limiting the supply of oil to the spindle which comprises, a casing provided with a longitudinal bore for receiving a bolster member located within the casing bore, a bolster member provided with a bore forming a bearing for a spindle, a spindle rotatably mounted within the bore of the bolster member, a portion of the outer wall surface of said bolster member being spaced from the inner surface of said casing to provide an oil reservoir between the bolster member and casing which is out of direct communication with the spindle bore, means in the casing providing an oil supply source communicating with said reservoir, and spaced means located between said bolster member and the inner surface of the casing wall above and below the said reservoir for permitting a restricted flow only of oil from said reservoir to that portion of the casing located outwardly of said bolster member and below said oil reservoir for supply to said spindle bearing, the several parts being so proportioned as to restrict the flow of oil downwardly from said reservoir to such an extent that the amount of oil carried upwardly about the spindle within the bore of the bolster is limited to such a degree as to prevent accumulation of oil within the casing above the uppermost spaced oil restricting means in quantities sufficient to overflow the casing.

RUDOLPH A. KOWALSKY.
